UNITED STATES PATENT OFFICE

ROBERT F. BRACKE, OF CHICAGO, ILLINOIS, ASSIGNOR TO CURTISS B. CAMP, TRUSTEE,
OF GLENCOE, ILLINOIS

CARBURETOR

Application filed September 26, 1925. Serial No. 38,696.

This invention relates to carbureting devices for multiple cylinder internal combustion engines, and is expressly designed for the delivery of fuel through different nozzles 5 for serving different cylinders of the engine. Great difficulty is often experienced in properly and equally distributing the fuel and air from a single carburetor to a plurality of cylinders, so that all of the cylinders will 10 receive the same quality of mixture, and will therefore produce explosions of equal length. The particular embodiment of my invention here illustrated is associated with a carburetor of the fuel lifting type, that is, one 15 wherein the suction derived from the engine lifts the fuel from a low level supply tank to the carburetor, from which it is delivered to the engine cylinders mixed with air. The particular type of fuel lifting device here 20 illustrated is arranged for regulating the flow of fuel to the nozzles of the carburetor, in accordance with the height to which the fuel is lifted from the low level supply tank, by 25 means of a valve located in the fuel line and controlled as to its degree of opening by a diaphragm, one side of which is subjected to atmospheric pressure and the other side to the suction of the engine intake on the carburetor nozzles. While it is not essential that 30 this particular type of fuel-controlling mechanism be used with my invention, it has particular utility when used therewith since it provides means for maintaining the fuel for 35 delivery to the nozzles at a constant pressure considerably less than that of the atmosphere, which, as will be later pointed out, assists in preventing the delivery of fuel from the nozzles of my fuel carburetor device at times 40 when fuel delivery from the nozzles is not desired. My invention is illustrated in the accompanying drawings, in which

Figure 1 represents an automobile chassis and shows the relative location of the fuel supply reservoir and the fuel feed and carburetor mechanism of my invention;

Figure 2 is a vertical section through the valve mechanism which serves to control the air inflow to the engine manifold and the 50 valve mechanism which serves to control the

fuel flow to the nozzles and to maintain the latter under a constant negative head;

Figure 3 is an elevation of my invention as applied to a four-cylinder automobile engine 55 block; and

Figure 4 is a horizontal section taken on the line 4—4 of Figure 3.

Referring to Figure 1, the chassis there illustrated is of conventional form and is provided at the rear with a fuel reservoir 6 connected by tubing 7 with the fuel controlling valve 8 illustrated in detail in Figure 2. Pipes 9 and 10 carry the fuel from the fuel regulating valve mechanism 8 to separate nozzles 12 and 13 mounted in the manifold 14 which is attached to the engine block 15. An air valve housing is shown at 16 for regulating the incoming air which branches in the manifold 14 and passes to the engine block and the cylinders past the throttle valves 17 70 and 18 shown in their wide open positions in Figure 4.

With this general outline of my invention, I will now describe the detail construction of the fuel valve 8 which, as before stated, serves to maintain a supply of fuel under substantially constant depression and holds it ready for delivery to either of the nozzles which, by the degree of suction produced thereon, demands a fuel delivery. The housing 8 is 80 provided with a cover 20 which screws into the upper portion of the housing, the housing and cover being provided with registering circumferential seats 21 and 22 between which a thin metal diaphragm 23 is clamped. The space above this diaphragm is in communication with atmosphere through a bore 24 in the centrally located plug 24, while the space below the diaphragm is in communication with the carburetor nozzles through 90 the pipes 9 and 10. The communication between the space below the diaphragm and consequently between the pipes 9 and 10 and the main low level supply tank 6 is controlled by the valve 25 resting upon a seat 26, the valve being pressed against this seat by spring 27 and having its upper end in contact with the central portion of the diaphragm 23 so that it will be opened thereby when the diaphragm is drawn downwardly by suction 100

derived from the depression in the fuel lines 9 and 10 extending to the nozzles. The spring 28 acts upon the diaphragm 23 to assist in opposing the movement of the diaphragm under the influence of the suction derived from the depression in the fuel lines 9 and 10. The lower portion of the valve body 8 is provided with a fuel inlet port 30 shown in Figure 3 and which communicates with the annular space 31 (Fig. 2). A screen 33 is interposed in the path of fuel between the space 31 and the interior 34 from which fuel passes upwardly into the chamber serving the valve 25.

15 The air valve housing 16 encloses a valve plate 37 mounted upon a stem 38 and normally resting upon a circumferential seat 39 formed in the housing 16. The enlarged lower end of the stem 38 constitutes a piston 40 working in the cylinder 41 formed in the housing 16 and serves as a dashpot to prevent fluttering of the valve 37. The dashpot action of this valve also serves to prevent the rapid opening of the valve 37, thus providing a slightly increased suction in the chamber 42 as the valve 37 tends to open, this suction serving, as will be hereinafter pointed out, to provide a slightly enriched mixture at the time the engine is accelerated.

20 The valve 37 is held normally closed by means of a spring 43 abutting on the one hand within the hollow portion of the piston 40 and on the other hand the under side of the partition separating the cylinder 41 from the air intake passage 44 from which the air is drawn past the valve 37 when the valve opens. The entrance to the air intake passage 44 is controlled by a choke throttle of any desired form, the lever 46 being shown as means for

25 closing this choke, the purpose of which is to provide a great restriction to the inflow of air for starting the motor. This restriction to the inflow of air, will increase the depression in manifold and tend to enrich the mixture entering the cylinders, hence starting will be facilitated. A weak spring 45 opposes the action of the spring 43 and is made adjustable for the purpose of delicately regulating the degree of suction at which the

30 valve 37 opens, this adjustment being important to obtain the correct mixture for idling the motor.

35 The air chamber 42 is in direct communication with the central portion of the manifold 14, the latter conducting the flow of air, as before described, to the openings in the cylinder block. A pair of Venturi nozzles 12 and 13 are mounted in direct alignment with the openings into the engine block. As shown in Fig. 4, the Venturi nozzle consists of a cylindrical aperture 100, at the base of which is a bell-shaped entrance 101, leading to a narrow throat 102. Upon enlargement of the throat, the walls give way to dip 103, which

40 leads away to a uniformly enlarged chamber

104, whose mouth is in the throat of Venturi tube 48. Immediately below the dip are small holes 105, uniformly spaced in the circumference of the tube, communicating with the annular space 106 which is the outlet of the fuel pipe 9. The outer aperture is protected by a cap 107, which is held in position by a cotter-pin 108 engaged in coinciding holes in the cap and hollow cylinder. The lower edge of the cap is perforated to allow entrance of air. Both nozzles are of similar design and are mounted in the manifold and are arranged to draw in a small amount of air, the diameter of the throat of the nozzle being so small that under the idling condition of the motor when the air demand is least, the restriction imposed to the passage of air through the Venturi tubes 12 and 13 will not relieve the vacuum in the manifold 14; there being even under this condition a small amount of air drawn into the manifold through the air valve 37. The ends of the nozzle Venturi tubes 12 and 13 extend into the throats of other Venturi tubes 47 and 48. The anterior ends of these Venturi tubes receive their air from the manifold, whereas, as heretofore described, the anterior ends of the Venturi tubes 12 and 13 receive their air from without the manifold and at atmospheric pressure. Throttle 17 and 18 are each connected to individual shafts 49 and 50, which are connected to levers 51 and 52 respectively. These levers being held in contact one with the other by a spring 53 and being made relatively adjustable by a screw 54 so that the throttles 17 and 18 may be adjustably closed and opened to allow the same volume of mixture to be fed to the different cylinders in the engine, thereby attaining explosions of equal strength in the cylinders. This is particularly necessary during the idling condition of the motor, at which time a very slight difference in the positions of throttles 17 and 18 will make a noticeable difference in the strength of the explosions. The two throttles thus described are operated by means of a linkage not shown, which is preferably connected with the end 55 of lever 52.

50 In the operation of the motor the nozzles 12 and 13 function very much as two separate carburetors with the exception that they are caused to deliver fuel in unison or synchronism with the suction stroke of the cylinders which the particular nozzles serve and are caused to withhold their fuel during non-suction periods by the arrangement of parts hereinafter more fully explained in connection with the operation of the device. In a four-cylinder motor, such as diagrammatically illustrated in Figure 1, it is customary that the motor valves be arranged so that the suction strokes of the cylinders occur in an order causing alternate periods of suction and non-suction for each of the two

entrances into the cylinder block. The arrangement of suction strokes will usually be (numbering the cylinders 1 to 4 from the front of the engine block) 1, 4, 2 and 3, though the order of suction strokes may, in some instances, be 1, 2, 3 and 4. In either case, the suction period occurring through the nozzle 12 will be followed by a non-suction period through that nozzle during which time a suction period will occur through the nozzle 13 followed by a second suction period through the nozzle 12 and a second suction period through the nozzle 13. The interior of the manifold 14 is maintained under a depression controlled by the valve 37 in order that there may be sufficient suction for lifting the fuel from the low level supply reservoir under all conditions of operation of the automobile upon which the carbureting mechanism of my invention is installed. This depression or suction in the manifold 14 is maintained by means of the springs 43 and 45 acting upon the valve 37 at such a degree that the suction created at the throat of the Venturi tubes 12 and 13 during the idling condition of the motor will be sufficient to lift fuel through a distance of substantially 40 inches. Such a suction will be maintained at the throats of the Venturi tubes 12 and 13 when a static suction equivalent to about 15 inches of gasoline is maintained in the manifold 14. The springs 43 and 45 are therefore given an initial compression requiring a suction in the manifold equivalent to about that necessary for maintaining a column of fuel 15 inches high before the valve 37 will be raised off its seat to permit the inflow of air into the manifold. When the engine is idling, therefore, at which time the fuel demand is the least, a very small amount of air is being taken in past the valve 37, but such an amount as does flow past the valve 37 passes alternately through the Venturi tubes 47 and 48. As this air passes through the Venturi tube 47 it creates upon the discharge end of the Venturi tube 12 a suction which is slightly enhanced over the static suction in the manifold 14 and maintained by the valve 37 and its associated springs. This slightly increased suction on the end of the nozzle 12 tends to draw fuel out of the pipe 10 and into the nozzle 12 at this moment, whereas the nozzle 13, which at this time is not subject to quite such severe suction, does not tend to draw fuel from the pipe 9. As before described, the pipes 9 and 10 both communicate with the chamber beneath the diaphragm 23 which controls the fuel valve 25. This diaphragm and its associated fuel valve and springs 27 and 28 serve to maintain a fuel depression in the chamber with which the pipes 9 and 10 communicate, which depression is substantially constant under variations in fuel demand as well as under variations in fuel lift. In assuming for the purpose of illustration that the springs controlling this diaphragm valve are set for maintaining a suction in the chamber below the diaphragm just sufficient for lifting fuel through a distance of 40 inches, then it will be understood that the suction on the ends of the nozzles 12 and 13 must be sufficient for creating slightly enhanced suctions at the throats of the Venturi tubes 12 and 13 where the fuel discharges into the air path, in order that fuel delivery will occur. The spring 45, which controls the delicate adjustment of the valve 37, is adjusted during the periods when any air flows through the large Venturi tubes 47 and 48. Normally the static suction on the ends of the Venturi tubes 12 and 13 causes a suction at their throats 102 and in the chamber below the diaphragm 23, and under this condition no fuel will be drawn out of the pipes 9 and 10 into the nozzles 12 and 13 excepting during the periods when the suction about the ends of the nozzles 12 and 13 is enhanced by the flow of air through the Venturi tubes 47 and 48. As the throttles 17 and 18 are opened, the flow of air to the cylinders increases, the suction on the ends of the nozzles 12 and 13 increases and consequently causes a proportionately larger amount of fuel to be drawn into the nozzles at each suction stroke. But between the suction strokes at the time when only static suction is acting upon the ends of the nozzles 12 and 13, the flow of fuel to the throats of these nozzles either entirely ceases or becomes so slight as to be negligible in the operation of the motor. What I have provided therefore by my arrangement of nozzles is an automatically operating fuel injection system receiving air from a common manifold, which is provided with a regulating valve which by its regulating action controls the amount of fuel delivered from the plurality of nozzles in timed relation with the suction strokes of the motor. It will be understood that the same system as herein disclosed may be applied to any number of cylinder inlets. For example, there may be a nozzle corresponding to 12 and a throttle corresponding to 17 for each cylinder of the motor instead of, as here illustrated, for each pair of cylinders, and the device, without other alteration than multiplication, may be used on a four-, six-, eight- or twelve-cylinder motor. It will also be understood that structural changes may be made without departing from the spirit or scope of the invention and if, on account of variation in level between the nozzle corresponding to 12 and the nozzle corresponding to 13 located at the extreme opposite ends of a common motor, the delivery is caused to be greater at one end than the other, the fuel feeding openings into one nozzle or the other may be made larger to compensate for this difference in level of the two nozzles or, if desired, more than one

diaphragm control valve may be used, each diaphragm control valve serving either one or more nozzles. It will also be understood that if it becomes desirable, in order to prevent back flow of fuel in pipes corresponding to 9 and 10, automatically operating check valves may be provided in these pipes permitting the flow of fuel in the direction toward the carburetor nozzles but preventing the flow of fuel in the opposite direction.

10 I claim:

1. In a carburetor, a plurality of nozzles each having a primary air induction passage therethrough, a common secondary air induction passage for said nozzles, an air valve for restricting the flow of air into said common secondary air passage, a chamber from which a plurality of said nozzles receives fuel including independent directly connected conduits from said chamber to each of said nozzles, means to maintain the fuel in said chamber under depression, said nozzles each having a primary air passage and the outer and adjacent the induction passage being positioned in branches with said secondary air passage and having one end exposed to the atmosphere, each branch being restricted about its nozzle whereby the flow of air from the secondary air passage past the nozzle creates a suction on the nozzle for drawing fuel from said fuel chamber.

2. In a carburetor, the combination with an induction passage having branches leading to different cylinders of an internal combustion engine, separate nozzles, each having a primary air passage therethrough one for each branch of said induction passage and having one end exposed to the atmosphere, a fuel chamber, branch conduits from said fuel chamber to restrict portions of said nozzles for delivery of fuel thereto, an adjustable diaphragm actuated spring valve having one side subject to atmospheric pressure for maintaining the fuel in said fuel chamber under a depression less than atmosphere, a valve controlling the inflow of air to said common induction passage, said valve being so adjusted that the minimum depression which it maintains in the common induction passage on a suction stroke in each cylinder when the air is passing or when there is suction in the induction passage is insufficient for drawing fuel out of said fuel chamber.

3. In a carburetor, the combination with an induction passage having branches leading to different cylinders of an internal combustion engine, separate nozzles, each having a primary air passage therethrough, one for each branch of said induction passage, a fuel chamber, independent branch conduits extending directly from said fuel chamber to said nozzles for delivery of fuel thereto, means for maintaining the fuel in said fuel chamber under a depression less than atmos-

phere, and a valve controlling the inflow of air to said common induction passage.

4. A carburetor for multiple cylinder engines, comprising a secondary air induction passage having branches extending to the intake of different cylinders of said engine, an air valve for restricting the flow of air into said secondary air passage, a fuel chamber, Venturi tubes, one for each branch of said secondary air passage projecting into said branches and having their intake end exposed to the atmosphere, a fuel conducting passage extending directly from said fuel chamber to the throat of each of said Venturi tubes, and throttle means for controlling the flow of air through the secondary air passage.

5. In a carburetor, the combination with an induction passage having branches leading to different cylinders of an internal combustion engine, separate nozzles, one for each branch of said induction passage, a fuel chamber, branch conduits extending directly from said fuel chamber to said nozzles for delivery of fuel thereto, means for maintaining the fuel in said fuel chamber under a depression less than atmosphere, a valve controlling the inflow of air to said common induction passage, said valve being so adjusted that the minimum depression which it maintains in the common induction passage is insufficient for drawing fuel out of said fuel chamber, the flow of air from the common induction passage past said nozzles in the various branches serving to alternately create a suction on said particular nozzles past which the air is flowing to withdraw a proper amount of fuel from said fuel chamber for mixing with the air to create a combustible mixture.

6. A carburetor having a plurality of nozzles positioned in branch air conduits extending to different cylinders of a multiple cylinder engine, a common restricted secondary air intake and a common fuel chamber including directly connected branch conduits from the fuel chamber for said nozzles, means for maintaining the fuel in said fuel chamber under depression, means for restricting the flow of air to the common secondary air intake passage to such an extent as to create a static suction on the nozzles in the branches to the various cylinders, which suction is insufficient for overcoming the depression in the fuel chamber, the alternate flow of air past the nozzles, however, at the time of the suction stroke of the particular cylinder served by a particular nozzle acting to increase the static suction in the secondary air intake passage sufficient to draw fuel from the fuel chamber and out of the particular nozzle.

7. A carbureting device for multiple cylinder engines comprising an induction passage having branches extending to the intake of

different cylinders of said engine, a separate throttle for each branch, a nozzle for each branch anterior to the throttle in said branch, a Venturi tube in each branch into the throat on which the nozzle for its branch extends, 5 each nozzle having its outer end provided with restricted communication to the atmosphere, and a common fuel chamber having separate fuel passages extending directly therefrom to each of said nozzles at the restricted portions thereof, from which fuel is 10 individually fed to said nozzles.

8. A carburetor having means of connection with an air induction passage of an internal combustion engine, an air inlet for the 15 passage communicating directly with the atmosphere, a fuel chamber having a conduit extending directly therefrom in communication with the passage, means to maintain the fuel in said chamber under depression less than atmospheric and a valve for regulating the inflow of air to the air induction passage.

9. A carburetor having means of connection with an intake manifold of an internal combustion engine, an air inlet for the 20 passage communicating directly with the atmosphere, a fuel chamber having a lead extending directly therefrom to the passage, means to maintain the fuel in said chamber under depression less than atmospheric and a dash pot controlled valve for regulating the supply of atmospheric air to the air induction passage to maintain said passage under depression to provide sufficient suction for lifting the fuel under all conditions of operation.

10. A carburetor including an air valve comprising a housing having an inlet and a seat above the inlet, the housing having means of connection with an air induction passage of an internal combustion engine, a valve cooperating with said seat, a 40 spring controlled dash pot for said valve, another spring opposing the first spring, means for adjusting the tension of said springs, a fuel valve including a diaphragm exposed to atmospheric pressure centrally, a spring acting on said diaphragm at the side opposite that exposed to atmospheric pressure, a passage through the valve having a seat adjacent the diaphragm, a valve seated against the seat and adapted to be unseated by the diaphragm, 45 a fuel chamber controlled by said valve and having communication with each end of the intake manifold, a Venturi tube in each end, a nozzle in each end extending into the restricted portion of the Venturi tube, each nozzle having its outer end directly exposed to atmosphere, and means for simultaneously regulating the induction through each end of 50 the intake manifold.

11. A carburetor having means of connection with an induction passage of an internal combustion engine, a fuel chamber including directly connected leads from said 55 fuel chamber for communicating with the

passage, means to maintain the fuel in said chamber under depression, a valve for controlling the inflow of air to the induction passage, means to provide great restriction to the inflow of air to the induction passage 70 for motor starting, and a dash pot associated with the valve to maintain the same under a depression less than atmospheric.

In witness whereof, I hereunto subscribe my name this 11th day of August, 1925.
